2 SHEETS—SHEET 2.

UNITED STATES PATENT OFFICE.

FRANK H. SEIDEL, OF HARVEY, ILLINOIS, ASSIGNOR OF ONE-HALF TO LOUIS KREYSCHER,
OF HARVEY, ILLINOIS.

MULTIPLE MOLD.

No. 910,476.

Specification of Letters Patent.

Patented Jan. 19, 1909.

Application filed May 14, 1908. Serial No. 432,785.

To all whom it may concern:

Be it known that I, FRANK H. SEIDEL, a citizen of the United States, residing at Harvey, in the county of Cook and State of Illinois, have invented a certain new and useful 5 Multiple Mold, of which the following is a description.

My invention relates to a mold adapted for casting large numbers of similar articles with 10 the least possible expense of time and labor both in the casting and the finishing of the product.

The object of my invention is to provide a simple, serviceable, and convenient device of 15 the kind described, and one arranged to release and discharge the articles from the mold as soon as possible after the casting operation by the mere opening or separating of the mold parts.

20 To this end my invention consists in the novel construction, arrangement, and combination of parts herein shown and described, and more particularly pointed out in the claims.

25 In the accompanying drawings, wherein like or similar reference characters indicate like or corresponding parts; Figure 1 is an end elevation of my device. Fig. 2 is a section taken substantially on line 2—2 of Fig. 30 3. Fig. 3 is a section taken substantially on line 3—3 of Fig. 1; and Fig. 4 is a plan view of my device.

In the form shown in the drawings, my 35 mold is adapted for casting sash weights, and comprises two substantially duplicate mold members 1 and 2 provided with recesses 3—3 in their proximate faces. As shown each member is chambered or hollow and provided with an inlet 4 and outlet 5 so that wa- 40 ter or other suitable cooling fluid may be permitted to flow through the member to control its temperature when in use.

The recesses 3—3 may be of any desired 45 form, size, or arrangement. As shown each recess consists merely of a semi-cylindrical groove or channel extending transversely of the mold member, with the lower end of each recess closed and so arranged that when the members are in casting relation to each other 50 a recess in one mold member will coöperate with a recess in the opposite mold member to form a cylindrical opening extending from the top towards the bottom of the member, and adapted to receive molten metal or other

substance from which it is desired to form 55 the articles.

Any suitable form of closure 6 may be provided in the recesses 3. As shown these closures are adapted to form the upper or eye portion of the sash weight and for that purpose are each arranged to produce the desired shape of this portion of the weight and provided with a projection 7 to form the opening for the reception of the sash cord. The closure 6 may be secured in position in 65 any suitable manner. In the form shown each closure is adjustably positioned in its particular recess 3 and secured in place by means of a cap-screw 8 for which a plurality of threaded openings 9—9 are provided in the 70 back of the recess 3 so that the closure 6 may be adjusted longitudinally of the recess to control the length of the weight to be cast.

Any suitable means may be provided to 75 control the relative position of the members 1 and 2. As shown the member 1 is rigidly secured in any desired manner to a base 10 as for example by the set-screws 11. The base 10 is preferably of suitable length to extend beyond the side of the member 2 when 80 the same is in casting position and is there provided with a suitable bearing 12. A shaft 14 or equivalent means is rotatably mounted in the bearings 12 upon the member 10 and provided at each end with an arm 15 keyed 85 or otherwise rigidly secured thereto. The free end of the arm 15 is pivotally connected by a link 16 or other suitable means to the central portion of the member 2. The link 16 is provided with a sleeve-nut 17 or other 90 suitable adjusting means intermediate its ends so that the relative positions of the opposite ends of the member 2 may be controlled as desired to equalize the pressure between the mold members. A lever 18 or 95 other convenient means is provided at a suitable point upon the shaft 14 for rotating the same and controlling the position of the member 2.

In the form shown a suitable spring actuated pawl 19 is provided upon the lever 18 adapted to engage a segment 20 to control the position of the lever.

Any suitable means may be provided for 100 directing the metal or other material into 105 the mold cavities 3—3. In the form shown a pair of hollow blocks 21—22 are provided upon the members 1 and 2 respectively with

the proximate faces of the blocks suitably formed to provide a channel or runner extending along the top of the mold above the several recesses of the mold, with a separate 5 opening 25 in the bottom of the runner communicating with each mold cavity. Each of the blocks 21 and 22 are provided with an inlet 26 and an outlet 27 for conducting water or other cooling fluid into, and away 10 from, its interior.

The block members 21—22 may be secured to the members 1 and 2 in any suitable manner, but as it frequently occurs that articles cast in a mold of this character tend to 15 strongly adhere to the walls of the mold cavity or the runner block I prefer to mount the blocks 21 and 22 loosely upon the top of the mold members and provide suitable means for controlling their position. In the 20 form shown a bracket 28 is provided at each end of the member 2 with a portion projecting upward at the ends of the blocks 21 and 22 to control their position longitudinally of the members 1 and 2.

25 The upper portion of the bracket 28 is preferably provided with a pair of slots or jaws 29 and 30 and a pin or projection 31 and 32 is provided upon the blocks 21 and 22 respectively extending into the slots and so 30 positioned that when the member 2 is moved to close the mold, that is, to bring its face in contact with the member 1 the pin 32 will be engaged by one wall of the respective jaw slots 29 to hold the face of the block 22 substantially even with the face of the member 2. As the member 2 moves toward the block 21 the face of the member 22 will engage the member 21 and carry the same into proper casting position when the mold is 40 closed.

In opening the mold in case the casing adheres to the walls of the member 1 or block 21 the member 2 and block 22 will move away from the casting until the end of the slot 30 45 engages the pin 31 upon the block 21 drawing it forward upon the member 1 and releasing the casting from the recesses 3—3. This movement also detaches the runner from its engagement with the block 21 permitting the 50 castings to fall through the space between the members leaving the mold entirely clear for the next casting operation.

In case the casting adheres to the member 2 or block 22 a slight movement of the block 55 22 upon the member 2 usually entirely detaches the same substantially as above described.

The operation of my device is very simple and rapid permitting very large quantities of 60 sash weights or similar articles to be formed with the least possible amount of labor and finishing. The molds being always substantially ready to receive the molten metal or other material of which the casting is to be 65 made.

If preferred suitable means in addition to the member 10 may be provided near the ends of my mold members to assist in maintaining the same in their proper relative positions. As shown a suitable rectangular bar 70 35 is rigidly attached at each end of the member 2 extending substantially parallel to the guiding face of the part 10. The free end of the bar 35 is slidably engaged in a bearing 36 rigidly attached to the end of the member 1 75 for this purpose.

While in the foregoing specification I have described the particular form of mold adapted for use in casting sash weights it is obvious that a great variety of articles may be formed 80 in molds of this character and as any amount of finish may be imparted to the mold faces desired the castings produced may have an extremely smooth surface requiring very little or no labor in finishing the same. It is 85 also obvious that immaterial modifications may be made in my device without departing from the spirit of my invention, hence I do not wish to be understood as limiting myself to the exact form and construction shown. 90

What I claim as new, and desire to secure by Letters Patent is:—

1. A mold, comprising two similar relatively movable members, each provided with recesses in their proximate faces adapted 95 jointly to serve as mold cavities, guiding means connecting said members, and mechanism for controlling the movements and relative positions of the members, in combination with a pair of blocks loosely mounted 100 upon said members jointly forming a runner for directing a fluid into said mold cavities.

2. A mold, comprising two similar relatively movable fluid cooled members, provided with recesses in their proximate faces 105 adapted jointly to serve as mold cavities, guiding means connecting said members, and mechanism for controlling the relative positions of the members, in combination with a pair of blocks loosely mounted upon said 110 members jointly forming a runner for directing a fluid into said mold cavities.

3. A mold, comprising two similar relatively movable members provided with semi-cylindrical recesses extending across their 115 proximate faces adapted jointly to serve as mold cavities, guiding means connecting said members, and mechanism for controlling the relative positions of the members, in combination with a pair of blocks loosely mounted 120 upon said members jointly forming a runner for directing fluid to said mold cavities.

4. A mold, comprising two similar relatively movable members provided with a semi-cylindrical recess extending across their 125 proximate faces, adapted jointly to serve as a mold cavity, a movable closure for the lower end of each recess, guiding means connecting said members, and mechanism for controlling the relative movement and positions of the 130

members, in combination with a pair of blocks loosely mounted upon said members jointly forming a runner for directing fluid to said mold cavity.

- 5 5. A mold, comprising two similar relatively movable members provided with recesses in their proximate faces adapted jointly to serve as mold cavities, guiding means connecting said members, and mechanism for controlling the movements and relative positions of the members, in combination with a pair of blocks loosely mounted upon said members jointly forming a runner for directing fluid to said mold cavities, and
- 10 15 means for automatically moving said blocks when the mold is opened and readjusting the same when the mold is closed.

6. A mold, comprising two similar relatively movable members provided with recesses in their proximate faces adapted jointly to serve as mold cavities, guiding means connecting said members, and mechanism for controlling the relative positions of the members, in combination with a pair of blocks loosely mounted upon said members jointly forming a runner for directing fluid to said mold cavities; and means upon one of said members for automatically moving said blocks when the mold is opened and re-

30 35 40 adjusting the same when the mold is closed.

7. A mold, comprising two similar relatively movable members provided with recesses in their proximate faces adapted jointly to serve as mold cavities, guiding means connecting said members comprising a suitable bar for each end of said members rigidly attached to one member and slidably attached to the other, and mechanism for controlling the movement and relative posi-

45 tions of the members, in combination with a pair of blocks loosely mounted upon said members jointly forming a runner for directing a fluid to said mold cavities.

8. A mold, comprising two similar relatively movable members provided with re-

cesses in their proximate faces adapted jointly to serve as mold cavities, guiding means connecting said members, and mechanism for controlling the movement and relative positions of the members, in combination with a pair of fluid cooled blocks loosely mounted upon said members jointly forming a runner for directing a fluid to said mold cavities.

9. A mold, comprising two similar relatively movable fluid cooled members provided with semicylindrical recesses extending across their proximate faces adapted jointly to serve as mold cavities, a movable closure for the lower end of each recess, guiding means connecting said members, and mechanism for controlling the movement and relative positions of the members, in combination with a pair of blocks loosely mounted upon said members jointly forming a runner for directing a fluid to said mold cavities.

10. A mold, comprising two similar relatively movable fluid cooled members provided with semi-cylindrical recesses extending across their proximate faces adapted jointly to serve as mold cavities, a movable closure for the lower end of each recess, guiding means connecting said members, and mechanism for controlling the movement and relative positions of the members, in combination with a pair of blocks loosely mounted upon said members jointly forming a runner for directing a fluid to said mold cavities, and means for automatically moving said blocks when the mold is opened and readjusting the same when the mold is closed.

In testimony whereof, I have hereunto signed my name in the presence of two subscribing witnesses.

FRANK H. SEIDEL.
